UNITED STATES PATENT OFFICE.

EDITH W. LOCKE, OF CHICAGO, ILLINOIS.

THERAPEUTIC LAMP.

No. 909,627.

Specification of Letters Patent.

Patented Jan. 12, 1909.

Application filed September 16, 1908. Serial No. 453,349.

To all whom it may concern:

Be it known that I, EDITH W. LOCKE, a citizen of the United States, and a resident of Chicago, in the county of Cook, in the 5 State of Illinois, have invented certain new and useful Improvements in Therapeutic Lamps; and I do hereby declare that the following description of my said invention, taken in connection with the accompanying 10 sheets of drawings, forms a full, clear, and exact specification, which will enable others skilled in the art to which it appertains to make and use the same.

This invention has general reference to 15 improvements in therapeutic lamps for medical, surgical and other curative purposes; and it consists, essentially, in the novel and peculiar combination of parts, and details of construction, as hereinafter 20 first fully set forth and described, and then pointed out in the claims.

In the drawings already referred to, Figure 1 is a longitudinal sectional elevation of my improved therapeutic lamp. Fig. 2 is a 25 transverse-sectional, inverted, plan in line $\alpha\alpha$ of Fig. 1 looking in the direction of an arrow. Fig. 3 is an inverted plan of the cap for the lamp-attaching fixture. Fig. 4 is a sectional elevation of the same in line 30 $y\gamma$ of Fig. 3. Fig. 5 is a perspective view of the tubular attaching means by which the cap and the lamp-attaching elbow are securely united. Fig. 6 is a plan with the cap removed. Fig. 7 is a sectional elevation of a 35 portion of the lamp-attaching fixture, the cap being removed, said figure being drawn on the line $z\zeta$ of Fig. 6.

Like parts are designated by corresponding 40 letters and characters of reference in all the figures.

The object of this invention is the production of a therapeutic, electric lamp used in surgical, medical and other treatments of diseases of the human body, in which 45 various defects which my experience with such lamps have demonstrated and disclosed, shall be effectually overcome. In using these lamps, I have found that the intense heat radiated by the lamp within the 50 confining space of a surrounding jacket and reflected by a powerful reflector, has a tendency to break the glass bulb of the electric lamp, and that injuries to the patient under treatment, sometimes of a very serious 55 nature, result from such breakage. I

have also discovered that the attachment of the glass bulb to the lamp is defective inasmuch as it requires considerable time in order to remove and replace a broken bulb. All these objections and others not necessary to particularly point out, are overcome in the improvements in my lamp, which improvements I shall now proceed to describe in detail.

A, in the drawings, represents the usual 65 electric incandescent lamp which, for the purpose of therapeutic treatment, is of great heat, and light-giving capacity, and which lamp is receiving its electric current or energy by the leads or wires B. This lamp 70 is suspended from the attaching body C by means of four metallic spring-like prongs, D, which, as shown in Figs. 1 and 7, are peculiarly curved to embrace the neck α of the lamp-bulb A, reinforced by an endless coil-spring E, shown in Fig. 1, acting 75 upon the outer surfaces of said prongs to tightly hold the lamp A in position.

C, as heretofore mentioned, is the lamp-attaching body. It consists of two separate 80 parts C and C¹, the latter serving as a base-piece to which the former is attached and also as a separator to prevent any possible arcing between the electrical conductors or wires B¹ B¹: this body C consists of a circular disk having on its under side an oblong projection b, which forms the separator of the two wires B¹ B¹, there being through the circular disk two apertures b¹, Figs. 6 and 7, through which screw threaded-rods b² are 85 passed to the lower ends of which knurled nuts c are screwed and then binding posts F 90 screwed below the knurled nuts c. The body C¹ is secured to the attaching-body by means of nuts c¹ at the upper end of said rods b² in 95 a manner hereinafter to be referred to, there being lock nuts c², on said rods to prevent the screw-threaded rods from dropping out of position when the upper nuts c¹ are removed.

The attaching-body C, is a circular, slightly tapering, body having an annular, slightly downwardly projecting flange C². In this attaching-body there are four diametrically opposite apertures d, and two 100 other, similarly located apertures d¹, the former to receive the shanks e of the four prongs D, and the latter to permit the passage of screw-bolts G, having thumb-nuts g at their upper ends, the heads of said bolts 110

being located in enlargements or counter-bores at the lower end of the apertures d^1 .

The prongs D are inwardly-bent near their upper extremities at d^2 , and again bent to form the shanks e. The portion d^2 of these prongs is located between the lower portion C and the upper portion C of the attaching body, and securely clamped there-between when the knurled nuts c^1 are drawn taut; 10 insulating and non-conducting media H, Fig. 7 being placed between the two bodies C C¹ to avoid any metallic contact and at the same time prevent heat from being communicated to the upper body C and parts connected therewith.

I, Figs. 1, 3 and 4, is the cap for the attaching-bodies, C C¹. It is a shell composed of preferably porcelain the same as the bodies C C¹, and having in its head i an upwardly projecting extension or boss i^1 . Within this shell are located, at diametrically opposite places, two metallic contact-pieces J having downwardly projecting lugs j , and also downwardly projecting binding posts, j^1 , said contact-pieces with their pendant lugs and binding-posts being secured in said shell by means of screws j^2 .

The insulated or electric conducting cord B enters the cap through the branch k of an elbow K, and thence downwardly, where the two conducting wires k^1 k^2 are bared and their ends secured in the binding-posts j^1 . The elbow K is held in position by a tubular sleeve L, shown in detail in Figs. 3, 4 and 5, said sleeve L having an external screw-thread m, wherewith engages a lock nut m^1 , Fig. 4, and having at its lower end two radially projecting lugs m^2 , which lugs enter similarly shaped recesses f, Fig. 3, thereby 40 preventing the sleeve from turning in the cap and also avoiding its being pulled out of said cap, the lock-nut m^1 being provided to securely hold the sleeve L in said cap. The upper branch of this elbow is internally 45 screw-threaded to receive a coupling nut N, Fig. 1, by means of which a supporting arm P is revolvably and removably attached to the elbow, said arm P being bent, as shown, and connected with its lower end to a hood Q, which will hereinafter be more fully referred to.

Upon the upper surface of the attaching-body C and held by the nuts c^1 upon the screw-threaded rods b^2 , there are located two 55 contact forks O, Figs. 6 and 7, wherewith engage the downwardly projecting lugs j of the contact-pieces J, to connect the conducting wires k^1 k^2 with the binding-posts F, Fig. 7, and through the rods b^2 and from the 60 binding-posts F through the wires B B¹, already mentioned, with the filament of the lamp A in the usual manner.

It will now be observed that, to break the circuit, and remove the lamp A, the thumb-nuts g are removed from the bolts G when

the entire cap I, may be removed from the attaching-body C, and the knife switches composed of the lugs j, on the contact-plates J, and the companion members of the fork O disengaged, the conductors B B¹ disengaged 70 from the binding-posts F, and then the lamp disengaged from the prongs D by removing the spring E and pulling the lamp A out of contact with said prongs. In this manner a broken or burned-out lamp A may be readily 75 removed and a new one placed into position in a very short space of time.

I have heretofore mentioned the hood Q. This hood is a cylindrical shell having a tapering section Q¹, the upper end of which 80 has an inwardly-projecting flange q, by which the hood Q is held in position, said flange q being clamped between the outwardly projecting flange C² on the attaching member C and the lower edge of the cap I, 85 as clearly illustrated in Fig. 1. This hood has on its lower cylindrical portion a handle R by means of which it and, in fact, the entire apparatus, is manipulated, and it has also a peep-hole S through which observations may be had. In the tapering portion Q¹ there are three (more or less) outwardly-forced projections n, which form within the tapering portion depressions within which a reflector T, of less diameter than the cone 90 at the place where the reflector is located, is supported by lateral projections t on said reflector entering said depressions. The reflector being smaller in diameter than the cone at its points of attachment, there is 100 afforded an annular space T¹, Figs. 1 and 2, forming a passage to allow a current of air to pass from the cylindrical shell through the cone, and out of the latter by apertures t¹ near the upper end of said cone. Thus a 105 current of cold air, entering from the open end of the hood, passes the lamp-bulb and through the annular space T¹, and escapes at the exit apertures t¹, thus keeping the lamp cool without interfering with the 110 therapeutic qualities of the heat and light rays emanating from the lamp filament U. This introduction of a current of cold air I have found during a series of experiments 115 extending over a sufficiently long term to prevent breakage of the glass bulb without interfering with the beneficial effects of said lamp.

Having thus fully described this invention, I claim as new and desire to secure to 120 me by Letters Patent of the United States—

1. As an improved article of manufacture, a therapeutic lamp consisting, essentially, of an incandescent lamp, an attaching body for said lamp composed of two separate attaching bodies and a cap, said parts being suitably connected together, a non-conductor of heat interposed between the two bodies forming the attaching medium, knife-switches interposed between the cap and up- 125

per attaching body, and a suitable hood secured to the upper attaching body and the cap, as described.

2. In an improved therapeutic lamp, an incandescent lamp, an attaching body for said lamp consisting of three separate parts properly secured together, downwardly projecting prongs secured to said attaching bodies between the upper and lower bodies, 10 and having shanks entering apertures in the upper body, a cap, contact pieces within said cap having knife-switch lugs and binding posts as described, contact forks upon the upper face of the upper attaching body 15 adapted to engage the knife-switch lugs, screw-rods passing through said attaching bodies, there being nuts at the upper ends of said screw rods to fasten the contact forks upon said upper body and lock nuts and 20 binding-posts at the lower ends of said screw rods whereby the two bodies composing the attaching body are secured one to the other, said screw-rods being also electric conductors for the current with which the incandescent lamp is supplied, a tubular sleeve in 25 said cap, said sleeve being provided with

lugs to prevent rotation, a lock nut on said sleeve to securely hold the sleeve in position, an elbow attached to said sleeve, an electrical conducting lead entering said elbow at its branch and having its bared wires engaging the binding posts on said contact pieces, and means for suspending the lamp in any desired angular or vertical position.

3. In a therapeutic lamp, a hood and reflector, said hood being a partly cylindrical and partly tapering shell, there being in said tapering portions depressions and exit openings, said reflector being of smaller diameter than the tapering shell at its point of suspension therein, whereby an annular space is afforded between the shell and the reflector, there being radially projecting lugs on said reflector engaging the depressions in the tapering portion of said hood.

In testimony that I claim the foregoing as my invention I have hereunto set my hand in the presence of two subscribing witnesses.

EDITH W. LOCKE.
